UNITED STATES PATENT OFFICE.

WILLARD C. ROBERTS, OF LINDENWOOD, ILLINOIS.

SPIKE.

1,255,108.

Specification of Letters Patent. Patented Jan. 29, 1918.

Application filed December 7, 1915. Serial No. 65,561.

To all whom it may concern:

Be it known that I, WILLARD C. ROBERTS, a citizen of the United States, residing at Lindenwood, in the county of Ogle and State of Illinois, have invented certain new and useful Improvements in Spikes, of which the following is a specification.

My invention relates to new and useful improvements in spikes and more particularly to a railway spike.

The primary object of the invention is the provision of a spike which is simple and inexpensive in construction and which may be easily driven into the desired object and held therein.

A further object of the invention is the provision of a spike having locking elements extending therethrough whereby the spike is held against vertical movement after having been driven into the desired article.

A still further object of the invention is the provision of a spike having a longitudinally extending shoulder to prevent lateral movement of the spike after having been driven in position.

With these and other objects in view the invention consists in the novel details of construction and arrangement of parts which will be more clearly understood from the following description and drawings, in which,

Figure 1 is a side view of the spike,

Fig. 2 is a transverse vertical section through the spike showing the locking element, and

Fig. 3 is a top plan view of the spike.

My spike comprises a body portion 1 having a head 2 formed on the top thereof, said head being provided with an extension indicated at 3 which is adapted to engage on the article, such as a rail, which is to be fastened in position. It will be understood that the extension 3 will pass over the base of the rail or other article. A portion of the body 1 is beveled longitudinally, as indicated at 4, thereby forming a shoulder at 5. It will be understood that the beveled portion 4 is formed on each side of the body portion of the spike, whereby there will be a shoulder 5 formed on each side thereof.

The lower end of the body 1 is beveled, as indicated at 6, thereby forming a sharpened edge whereby the spike may be easily driven into position. Longitudinal openings 7 are formed in the spike, said openings extending from the head 2 to a point midway the

body of the spike. These openings 7 extend at an angle and are laterally spaced apart, one opening extending to the right side of the spike and the other opening extending to the left side thereof. These openings are preferably formed in that portion of the body extending parallel with the beveled portion 4.

It is to be noted that the spike is approximately twice as wide as it is thick. The shoulders 5 are extended longitudinally and serve to divide the body portion of the spike into approximately two distinct portions, one being similar to the conventional form of spike and the remaining portion being beveled or wedged shape.

Locking elements in the form of keys 8 are adapted to be passed through the openings 7 and these keys have the heads 9 formed on the upper ends thereof. The upper ends of the openings 7 are preferably enlarged, as indicated at 10 in Fig. 3 of the drawings, to receive the heads 9 of the locking keys 8. These locking keys are preferably formed of soft metal and are slightly curved outwardly, particularly the ends, whereby the ends will flare outwardly, as is clearly shown in Fig. 2 of the drawing, when driven into position. The keys will be forced outwardly from the beveled surface of the wedged shape portion and, therefore, will have more of a tendency to flare outwardly than would be the case if the openings terminated in the straight portions of the spike.

Having fully described the details of construction it is thought that the advantages and mode of use will be clearly understood. It is the object of my invention to provide a spike, particularly adapted for railways, which may be locked in position after having been driven. The sharpened edge 6 will allow the spike to be easily driven into the tie or other article whereby the projection 3 formed on the head will extend over the base of the rail or other article to be secured. The shoulders 5 formed on each side of the spike will prevent the lateral movement of the spike after having been driven in position. After the spike has been driven and it is desired to lock the same, the locking keys 8 are driven through the openings 7 and when the ends of said keys engage the tie or other article they will be flared outwardly and upwardly as is clearly shown in Fig. 2 of the drawing. When such keys

have been driven in position, it will be impossible for the spike to have any vertical movement upwardly and will therefore not be worked loose by any jar upon the article 5 it is securing. If it is desired to remove the spike it is only necessary to withdraw the locking keys 8 which can be done by engaging any suitable instrument beneath the heads 9 of the keys. After the keys have 10 been withdrawn from the openings 7 the spike can then be withdrawn.

Having fully described my invention what I claim as new and desire to secure by Letters Patent is:

15 1. A spike comprising a body portion, the width of the body portion being approximately twice the thickness of the body portion, shoulders extending longitudinally for a portion of the length of the spike on each 20 side thereof, the surface of each side of the spike being beveled at one side of each shoulder, the said spike being provided with diagonally extending openings opening in the said beveled surfaces at each side of the spike, and a key adapted to be arranged in each of the said diagonal openings.

2. A spike comprising a body portion having a pair of longitudinally extending shoulders formed thereon, each side surface 30 of the spike being beveled whereby the beveled surface is flanked by the corresponding shoulder, the said body portion having its lower end beveled to provide the sharpened end edge for the spike, the said beveled surface merging into the said beveled end, and keys carried by the said body portion and adapted to coöperate with the beveled sides 35 of the spike for preventing upward movement thereof.

40 3. A spike comprising a body portion of a width equal to approximately twice its thickness and having a portion of its side surface beveled to provide oppositely disposed shoulders, the said shoulders dividing the said body portion whereby one portion of the body simulates a conventional spike while the remaining portion is of tapered 45 formation, diagonally extended keys, the said keys being extended through diagonally disposed openings formed in the said 50 tapered portion, the said openings having their open ends in the head of the said spike.

4. A spike comprising a body portion of 55 a width equal to approximately twice its thickness and having a portion of its side walls tapered to provide a longitudinal shoulder at each side of the body, the portion of the body at one side of the shoulder 60 simulating a conventional spike, the remaining portion of the body being of tapered formation, the said tapered portion being provided with diagonally extending openings, each opening having one terminal 65 in one of the tapered sides of the said ta-

pered portion and its opposite terminal in the head of the spike, and a key mounted in each of the said openings.

5. A spike comprising a body portion of a width equal to approximately twice its thickness and having a portion of its side walls tapered to provide a longitudinal shoulder at each side of the body, the portion of the body at one side of the shoulder simulating a conventional spike, the remaining portion of the body being of tapered formation, the said tapered portion being provided with diagonally extending openings, each opening having one terminal in one of the tapered sides of the said tapered portion and its opposite terminal in the head of the spike, the end of the body of the spike being tapered to provide a sharpened end edge, the said tapered sides of the tapered portion merging into the said tapered end, keys arranged in the said diagonal openings, the said keys having their ends slightly curved outwardly for permitting them to curve when forced through the said diagonal openings.

6. A spike comprising a body portion, the said body portion having openings extending diagonally therethrough in opposite directions from the upper end of the spike, each opening terminating at one side of the spike and arranged in laterally spaced relation, and keys adapted to be thrust through the said openings.

7. A spike having openings extending diagonally therethrough, shoulders formed on each side of the spike and extending longitudinally thereof and keys adapted to pass through the diagonal openings each of the said openings terminating at opposite sides of the said spike and in a position whereby they will be flanked by the said shoulders.

8. A spike comprising a body portion having the lower end thereof beveled, one portion of the body simulating a conventional spike and the remaining portion being of wedged shape, shoulders formed on each side of the spike and extending longitudinally thereof, said spike having diagonal openings therethrough, the said openings terminating in the sides of the said wedged shape portion, and keys adapted to pass through the diagonal openings.

9. A spike comprising a body portion, one longitudinal half of which simulates a conventional spike, the remaining half being of wedge formation, a head formed on the end of the spike and having openings formed therein and extending diagonally through the wedge shaped portion in opposite directions.

10. A spike comprising a body portion, one half of which is formed to simulate a conventional spike, the other half being wedge shaped, the proximate side of the conventional shaped portion forming longi-

tudinal shoulders, and a head integrally formed with the conventional and wedge shaped portion, the wedge shaped portion having diagonally extending openings laterally spaced apart and opening at opposite sides on the wedge shaped portion of the spike, and fastening keys extended through the said openings.

11. A spike comprising a body portion of

relatively great width, one half of the body portion simulating a conventional spike and the other half being of wedge shape.

In testimony whereof I affix my signature in presence of two witnesses.
